DESIGN FOR AN OIL WELL POWER PUMP JACK

Earl Ginn, North Muskegon, Mich., assignor to
Continental Motors Corporation, Detroit,
Mich., a corporation of Virginia

Application December 12, 1941, Serial No. 104,598

Term of patent 14 years

To all whom it may concern:

Be it known that I, Earl Ginn, a citizen of the United States of America, residing at North Muskegon, in the county of Muskegon and State of Michigan, have invented a new, original, and ornamental Design for Oil Well Power Pump Jacks, of which the following is a specification, reference being had to the accompanying drawing, forming part thereof, in which:

Fig. 1 is a side elevational view of an oil well

power pump jack showing my new design, the other side thereof being substantially like the side shown,

Fig. 2 is a plan view thereof, and

Fig. 3 is a front end view thereof in reduced scale.

I claim:

The ornamental design for an oil well power pump jack, as shown and described.

EARL GINN.
